FIREMAN'S TOOL

Theodore Ziaylek, Jr., 140 Riverview Ave.,
Yardley, Pa.

Filed Apr. 21, 1971, Ser. No. 136,287

Term of patent 14 years

Int. Cl. D8—05

U.S. Cl. D8—81

FIG. 1 is a perspective view of a fireman's tool embodying my new design;

FIG. 2 is an elevation view of a first side of a fireman's tool as shown in FIG. 1;

FIG. 3 is an elevation view of a second side of a fireman's tool as shown in FIG. 1; and

FIG. 4 is a top plan view of a fireman's tool as shown in FIG. 1.

I claim:

The ornamental design for a fireman's tool, as shown.
